UNITED STATES PATENT OFFICE

LAWRENCE W. LUELLEN, OF NEW YORK, N. Y., ASSIGNOR, BY MESNE ASSIGNMENTS,
TO INDIVIDUAL DRINKING CUP COMPANY, INC., A CORPORATION OF NEW YORK.

DISPENSING APPARATUS.

1,336,469.

Specification of Letters Patent. Patented Apr. 13, 1920.

Application filed March 24, 1911. Serial No. 616,714.

To all whom it may concern:

Be it known that I, LAWRENCE W. LUELLEN, a citizen of the United States, residing in the city of New York, borough of Manhattan, county and State of New York, have invented certain new and useful Improvements in Dispensing Apparatus, of which the following is a full, clear, and exact specification.

10 This invention relates to dispensing apparatus and has for its object to provide a device of this character for containing and dispensing fragile articles. An instance of such is the sanitary drinking cup, which at 15 the present time is made from paper coated with a substance rendering the cup waterproof and self-sustaining, and, to a degree, brittle.

The present invention is designed to provide 20 storage for a quantity of fragile cups, exposing the cups one at a time in position for removal and at the same time protecting the stored cups, and also the interior and rim of the exposed cup, from dust and 25 contaminating contacts of all kinds, and so holding these stored cups that the partially-exposed cup may be readily removed without injury thereto.

In the drawings accompanying and forming 30 a part of this specification,

Figure 1 illustrates, partly in elevation and partly in section, a practicable embodiment of a form of my invention.

Fig. 2 is a horizontal section taken on a 35 plane indicated by the line 2-2 in Fig. 1, looking upwardly.

Fig. 3 is an enlarged elevation, partly in section, of a different form of the same invention; and

40 Fig. 4 is a top plan view of the dispensing apparatus illustrated in Fig. 3.

In Figs. 1 and 2, a support indicated by the numeral 5 is illustrated as a convenient means for supporting the device. This affords a base which may rest upon some horizontal surface, as for instance a table or shelf, and presents a vertical surface 6, to which suitably formed faces of the device may be attached. A reservoir 7 is provided 45 for the receptacles, which reservoir may be made of a glass cylinder having a suitable cover 8 for closing the top of the reservoir. The bottom of the reservoir is shown supported by a ring 9, which carries an inwardly-directed flange 10. This ring 9 has 50 a securing member 11, whereby it is secured

to the standard 5. Between the flange 10 and the lower edge of the reservoir cylinder 7, there is interposed an elastic gasket 12, which affords a sealing member between the 60 edge of the reservoir cylinder and the flange.

There is shown in the reservoir a pile of nested cups 13. The lowermost cup of the pile is shown in engagement with the gasket. Each of the cups is shown with an outwardly-directed flange at the rim or top 14, which flange in the lowermost top is shown resting upon the elastic gasket. The opening in the flange 10 is shown of a sufficient diameter to permit the flange of the cup 70 freely to pass through it, but the opening in the gasket is shown of a smaller diameter than the flange of the cup and also of a smaller diameter than the opening in the flange 10. This affords an elastically-yieldable 75 support for the bottom cup of the pile, and which support will yield upon the lowermost cup of the pile being pulled downwardly. The gasket will resume its normal position immediately after the passage 80 through it of the flange of the cup and assume a position where it will engage the next cup in the pile. The elasticity or yieldability of the gasket may be determined not only by the inherent characteristics of the 85 material of which it is made, the relative thickness, etc., but also by the relative diameters of the openings in the gasket and in the flange 10. By increasing the diameter of the flange 10 relatively to the diameter of 90 the gasket, more yieldability will be present in the gasket. And conversely, by decreasing the diameter of the flange 10 relatively to the diameter of the gasket opening, the yieldability of the gasket may be con- 95 stricted.

In some instances it may be desirable to increase the flexibility as it were, of the elastic supporting device for the cups, in which instance the cups may be supported 100 by a series of elastic yieldable fingers. In Figs. 3 and 4 such a device is illustrated, wherein the reservoir 20 is shown supported by a ring 21, provided with an inwardly-directed flange 22, the ring being supported 105 by an attaching device 23, which is slidable upon a standard 24, and may be secured in desired position of adjustment by means of a set-screw 25. The lower end of the cylinder 20 has interposed between it and the flange 22, an elastic gasket 26, provided with a series of fingers 27 and a series of

5 fingers 28. The series of fingers 27 project inwardly farther than do the fingers 28. This is for the purpose of giving an increased gripping action upon the cups 29, 10 which cups are shown provided with conical surfaces and unflanged, as in the showing in Fig. 1. By this means, as the cup assumes its normal position in the holder and as it is drawn out, it will be gripped at two 15 zones, one zone being gripped by the fingers 27 and the other zone by the fingers 28.

15 Further advantages of this construction may be readily seen from the reference to Fig. 3 of the drawing from which it will be noted the shorter fingers 28 first pass the edge of the downwardly drawn cup. These 20 fingers 28 then engage the next succeeding cup while the fingers 27 are still in engagement with the lowest cup. Upon further passage of the lowest cup downwardly, the 25 fingers 28 retain the next succeeding cup with which they have just come into engagement and prevent its following the first cup. When the lowest cup finally is withdrawn from the fingers 27 such fingers also 30 engage the next lowest cup. By the above construction, it will thus be seen that the next to the lowest cup is positively retained in place even before the lowest cup is completely removed.

35 From the above, it will be readily noted that the operation of this type of apparatus is radically different from one in which there is simply an annular ring or washer, 40 for, in the latter case, the lowest cup must be wholly removed before the next succeeding cup is engaged at any point by the annular ring or washer. This might permit one or more additional cups following the 45 first cup and being accidentally withdrawn from the device. However, applicant's construction above described insures withdrawal of only one cup at a time from the device under all conditions.

50 45 It will be seen from a reference to Fig. 4 that the gasket 26, together with the fingers 27 and 28, may be readily stamped in one operation from a sheet of elastically yielding material. The fingers normally lie in the same plane as the body of the annular ring of the gasket 26 when in unflexed condition.

55 Although in the present illustration of mechanism waterproof paper cups are referred to, yet it will be apparent that other articles may be dispensed in this device and that various changes may be made in the mechanism without departing from the spirit of my invention. It will also be understood that either flanged or unflanged 60 cups may be used with either form of apparatus illustrated and described.

What I claim is:

1. In a cup-dispensing apparatus, the

65 combination with a receptacle for a stack of cups, the receptacle being provided with a discharge opening, of a cup-support located at such opening and comprising a ring of elastically-yieldable sheet material carrying two series of inwardly-directed fingers, 70 one series projecting farther inwardly than the other, the fingers of one series alternating with those of the other series about such opening.

2. In a cup-dispensing apparatus, the 75 combination with a receptacle for a stack of cups, the receptacle being provided with a discharge opening, of a cup-support located at such opening and comprising two series of inwardly-directed elastically- 80 yieldable fingers disposed about such opening, one series projecting farther inwardly than the other.

3. In a cup-dispensing apparatus, the 85 combination with a cover-support, of a cup-support comprising two series of elastically-yieldable members for engaging the first cup of a series of cups about two spaced-apart zones.

4. A cup-dispensing device including in 90 combination a plurality of inwardly reaching fingers for engaging and supporting the cups, said fingers having their cup-engaging portions situated in a plurality of planes parallel with their plane of origin, the fingers having their cup-engaging portions in 95 one plane varying in pressure from those having their cup-engaging portions in another plane.

5. A cup-dispensing device including in 100 combination a plurality of inwardly reaching fingers for engaging and supporting the cups, said fingers having their cup-engaging portions situated in a plurality of planes parallel with their plane of origin, those 105 fingers having their cup-engaging portions in one plane being staggered circumferentially relatively to those fingers having their cup-engaging portions in another plane.

6. In a cup dispensing apparatus, the 110 combination of a receptacle for a stack of nested cups, the receptacle being provided with a discharge opening, of a cup support located at such opening, and comprising an annular ring of elastically yielding sheet 115 material carrying two series of inwardly directed integral fingers, one series projecting inwardly farther than the other and both series of fingers normally lying in the plane of the annular ring when in unflexed condition.

120 In witness whereof, I have hereunto set my hand in the presence of two subscribing witnesses.
